CLAIM

The ornamental design for a satellite dish feed horn cover, as shown and described.

DESCRIPTION

FIG. 1 is a top, front and right side perspective view of a satellite dish feed horn cover showing my new design;

FIG. 2 is a top plan view thereof;

FIG. 3 is a front elevational view thereof;

FIG. 4 is a right side elevational view thereof, the left side being a mirror image;

FIG. 5 is a bottom plan view thereof; and

FIG. 6 is a rear elevational view thereof, in reduced scale as compared to the other figures.

FIG. 1.

FIG. 2.

FIG. 3.

FIG. 4.

FIG. 5.

FIG. 6.
